UNITED STATES PATENT OFFICE.

CHARLES H. FRY, OF ERIE, PENNSYLVANIA, ASSIGNOR TO CHARLES H. FRY CONSTRUCTION COMPANY, OF ERIE, PENNSYLVANIA, A CORPORATION OF PENNSYLVANIA.

LOADING APPARATUS.

Application filed August 29, 1921. Serial No. 496,339.

This invention is designed to store and facilitate the loading of materials. It is particularly effective in the handling of materials for concrete work such as concrete roads. With such work it is usually desirable to have the different classes of material as broken stone, gravel, sand and cement and these should be very accurately proportioned. With the present invention this material is measured and delivered at one operation to a truck or similar conveyance so that it may be carried to the work without further handling and in proportions and quantity desirable for the position and convenient for handling.

The invention is illustrated in the accompanying drawings as follows:

- Fig. 1 shows a front view of the apparatus.
Fig. 2 an end view of the apparatus.
Fig. 3 an enlarged view of the transfer car.
Fig. 4 an end view of the transfer car.

Fig. 5 an enlarged plan view of an automatic locking device for a closure car.

Fig. 6 a plan view of the same parts.

1 marks a bin which is preferably hopper-shape and suspended from a frame 2 carried by suitable posts 3. A track formed of two rails 8 extends under the bins to a point in front of the bins. The tracks are carried by the beams 9 supported by the posts 3 and by beams 10 on front posts 11. The beams 9 are sufficiently elevated to permit a truck or conveyance 12 to pass under them in position to be loaded and the posts 11 are sufficiently in front of the front posts 3 to permit of such passage. A transfer car 15 is mounted on the track 8. It is provided with longitudinal sills 16 between which are arranged the wheels 17 on an axle 18. Cross beams 19 extend from the sills 16 and hopper-bottom compartments 4, 5, 6 and 7, each compartment having a capacity for one batch of one material are suspended from the beams 19. The compartments are each supplied with swinging doors 20 which continue the bottoms 21 and are connected with the bottoms by hinges 22. The doors are maintained in closed position by eccentrics or cams 23. These eccentrics are mounted on shafts 24 carried in bearings on a cross beam 25, the cross beam being supported by the hangers 26. Braces 27 extend from the hangers to the bottoms 21. Worm gears 28

are fixed on the shafts 24 and worms 29 mesh with the worm gears 28. The worms 29 are mounted on a shaft 30 and the shaft 30 is journaled in bearings 31 on the hangers 26. A hand wheel 32 is provided by means of which the shaft 30 may be turned and thus the cams operated to release and close the doors 20.

Cables 33 operate over sheaves 34 carried by the frame and are secured to the car at the front and rear. The cable operates over a drum 35 and the drum 35 is operated by a crank 36. The cable winds off and on the drum 35, that is to say, as the front cable is wound up the rear cable is unwound so that the car is moved forward and back.

A closure car 37 is mounted on the track 8. It has the sills 38 between which the wheels 39 are mounted on axles 40. Cross beams 41 are mounted on the sills 38 and carry the closure platform or shutter 42. The closure car is of such a height that when mounted on the tracks 8 and when moved under the bins 1 the platform will completely close the bins. The tracks extend sufficiently to the rear of the bins to permit the closure car to move to the rear of the bins permitting the transfer car to be brought under the bins for loading.

In order that the closure car may be operated automatically with the transfer car a hook 43 is secured to the side of the closure car and this is engaged by a latch 44 carried by the transfer car. The latch is pivotally mounted on a bracket 45 on the transfer car and has an arm 46 extending from it on which is mounted a roller 47. The roller operates along a guide 48 with a cam end 48a. A cam 49 supported by the frame is arranged in the path of the roller 47 and engages the roller to swing the latch 44 out of engagement with the hook 43. The guide 48 and cam 49 are so positioned that as the transfer car moves forward the closure car is also moved forward through the action of the hook 43. As the transfer car reaches a position bringing the closure car completely under the bins the roller 47 reaches the cam 49 and this disengages the hook 43 permitting the transfer car to proceed to a position over the truck. On the return movement the cams operate in a reverse manner to swing the hook to open position until the closure car is engaged and then to close the hook so as to lock the two cars together.

In the general operation of the device the transfer car is moved under the bins, the movement of the transfer car under the bins removing the closure car and immediately permitting the filling of the transfer car. The compartments of the transfer car are accurately arranged or proportioned to receive exactly the proper amount of material and as they move forward they are carried with the material just level with the top the front edges of the bins holding back and striking off any surplus and the closure car moves under the bins as the transfer car is removed. When the transfer car reaches a loading position over the truck the shaft 30 is operated, releasing all the doors and dumping at one operation all the compartments.

The truck is ordinarily provided with compartments corresponding to the compartments on the transfer car as the compartments 4^a, 5^a, 6^a and 7^a and these are separated by the partition plates 13 which are hinged to the truck at 14. As many bins 1 are used as there are different materials, ordinarily one for sand and one for stone. The truck is brought in position to receive material from the bin with rock and the rock dumped into each of the compartments 4^a, 5^a, 6^a and 7^a sufficient for a batch in each compartment. The truck is then brought into position opposite the second bin containing the sand and sand sufficient for a batch for each compartment is dropped into the compartments in the truck. When the truck reaches the work the different compartments of the truck are unloaded successively, each compartment carrying a batch.

40 What I claim as new is:—

1. In a loading apparatus, the combination of an elevated storage bin; a horizontal track extending under the bin and to a point in front of the bin and above a way; a transfer car on the track, said car having a plurality of compartments; means for dumping all the compartments on the car simultaneously; means for striking off the excess material on the car as the car is moved from under the bin; and means for opening the bin to fill the car and to close the bin.

2. In a loading apparatus, the combination of an elevated storage bin; a horizontal track extending under the bin and to a point in front of the bin and above a way; a transfer car on the track having compart-

ments; hinged bottoms for said compartments on the car; releasable devices holding the bottoms closed comprising cams and means for actuating the cams; means for striking off the excess material on the car as the car is moved from under the bin; and means for opening the bin to fill the compartments of the car and to close the bin.

3. In a loading apparatus, the combination of an elevated storage bin; a horizontal track extending under the bin and to a point in front of the bin and above a way; a transfer car on the track having compartments; hinged bottoms for said compartments on the car; releasable devices holding the bottoms closed comprising cams, shafts on which the cams are mounted, worm gears on the shafts, worms acting on the gears, and means for actuating the worms; means for striking off the excess material on the car as the car is moved from under the bin; and means for opening the bin to fill the compartments of the car and to close the bin.

4. In a loading apparatus, the combination of an elevated storage bin; a horizontal track extending under the bin and to a point in front of the bin and above a way; a transfer car on the track, said car having a plurality of compartments; means for dumping the compartments on the car; means for striking off the excess material on the car as the car is moved from under the bin; and means for opening the bin to fill the car and to close the bin when the car is removed comprising a closure car having a platform acting as a shutter for the bin the closure car having a connection with the transfer car operating the closure car with the transfer car to close the bin.

5. In a loading apparatus, the combination of an elevated storage bin; a horizontal track extending under and to a point in front of the bin and above a way; a transfer car on the track; means for dumping the transfer car; means for striking off the excess material on the car as the car is moved from under the bin; and means for opening the bin to fill the car and to close the bin as the car is removed comprising a closure car having a platform acting as a shutter for the bin, said closure car operating on the same track as the transfer car.

In testimony whereof I have hereunto set my hand.

CHAS. H. FRY.
